CLAIM

I claim the ornamental design for an industrial endoscope, as shown and described.

DESCRIPTION

FIG. 1 is a front elevational view of a first embodiment an industrial endoscope showing my new design;
FIG. 2 is a back elevational view thereof;
FIG. 3 is a left side elevational view thereof;
FIG. 4 is a right side elevational view thereof;
FIG. 5 is a top plan view thereof;
FIG. 6 is a bottom plan view of thereof;
FIG. 7 is a perspective view thereof;
FIG. 8 is a front elevational view of a second embodiment of an industrial endoscope showing my new design;
FIG. 9 is a back elevational view thereof;
FIG. 10 is a left side elevational view thereof;
FIG. 11 is a right side elevational view thereof;
FIG. 12 is a top plan view thereof;
FIG. 13 is a bottom plan view thereof;
FIG. 14 is a perspective view thereof; and,
FIG. 15 is a perspective view thereof where the industrial endoscope is shown in a changed status.
